8 Claims. (Cl. 48—176)

This invention relates to gasholders of the floating disc type in which a piston closure is movable vertically in a stationary closed tank. In this type of holder gas is admitted to the holder 5 below the piston closure which is loaded to a value corresponding to the desired pressure of gas.

It is the object of the invention to provide simple and efficient means for preserving the piston closure in its normal horizontal plane during its movement in the tank and while stationary.

It is a further object of the invention to enable an existing gasholder of the water type having a movable gas containing tank of the single or multiple lift type to be readily converted into a holder of the piston closure type and thereby form a holder of greater gasholding capacity with a minimum of structural alteration.

The floating piston closure according to the invention is maintained in a normal horizontal plane by at least three cables or chains each attached at one end to the fixed roof or to the upper part of the sides of the holder or tank and at the other end to the bottom of the tank at a point equidistant from the points of connection of the other cables, each cable being slidably connected to the piston closure at at least two points on a diameter of the disc.

Each cable may extend diametrically over or under the piston closure or alternatively may pass downwards from the piston closure at the central part thereof.

The piston closure may be loaded with concrete blocks in the known manner or may be dish-shaped to hold water which serves to load it.

The circumferential edge of the piston closure may be sealed in known manner.

According to the invention the guiding pulleys are carried in housings at the points where the 40 cables or chains pass from one of the zones formed by the piston closure to the other zone and sealing means are provided at these housings.

In the accompanying drawings:—

45 Figs. 1 and 2 show a side elevation and plan respectively of a construction according to the invention in which the cables or chains extend diametrically across the piston closure.

50 Fig. 3 is a sectional elevation showing the housings and sealing means.

Fig. 4 shows a side elevation of a modified construction in which the cables or chains pass downwards centrally of the piston closure.

Figs. 5 and 6 show a sectional side elevation and plan respectively of the centrally disposed 5 housings and sealing means.

Fig. 7 shows a diagrammatic sectional elevation of a gas holder which has been converted from a water type holder to one of the floating piston closure type.

Referring to Figs. 1, 2 and 3 the holder or tank 1 has a fixed roof 2 to which cables 3 are anchored at diametrically opposite points on a circumference corresponding to that of the piston closure 4. Each cable 3 passes downward, under 15 a pulley 5 carried by the piston closure 4 adjacent the periphery of the latter, and passes across said closure to a pulley 6 also carried by the closure. From the pulley 6 the cable enters through a conduit 7a, a housing 7 containing an 20 oil bath 8 (the conduit 7a entering the bath 8) and passing under a pulley 9 submerged in the oil bath and over a pulley 10, passes downwards through a conduit 11 which rises above the level of the oil bath 8, and through the disc to the 25 bottom of the tank 1 where it is anchored.

In the modified construction shown in Figs. 4, 5 and 6, the cables or chains 3' are anchored to the fixed roof 2' as in the construction described above at equidistant diametrically opposed 30 points. Each cable 3' passes downward and under

guide pulleys 5' at the outer rim of the disc and passes radially towards the centre of the disc. A centrally disposed housing 12 supports guide 35 pulleys 13 over each of which a cable 3' passes into the housing 12. The housing 12 forms an annular chamber 14 containing an oil bath 15.

The annular chamber 14 is divided by a circular member 16 extending downwardly from the cover 40 17 of the housing. At the lower end of the member 16 are carried guide pulleys 18 submerged in the oil bath 15. Each cable 3' passes under one of the guide pulleys 18 and over a

guide pulley 19 carried on the inner wall 20 of 45 the annular chamber 14. Each cable 3' after passing over a pulley 19 passes down through the piston closure 4 to the bottom of the holder or tank 1 where it is anchored.

In both the constructions described it will 50

be seen that the piston closure can only be tilted if the cables are able to stretch.

With cables of constant length any tilting tendency of the piston closure is resisted by the cables. With the construction according to the invention considerable movement of the piston closure towards the roof of the holder is permissible.

It will be seen that by braking the movement of the guide pulleys on the disc under which the cable or chain passes from the roof, for example by means of brake drums, the pressure exerted by the piston closure on the enclosed gas may be controlled. In a further modification, the cables may, after passing under the pulleys on the periphery of the piston closure, pass over a pulley in the roof and thence to a second pulley on the piston closure, and so to the centre or opposite side of the piston closure. Before reaching the anchoring point at the bottom of the holder, the cable may pass over a pulley on the bottom, thence to a pulley on the under side of the piston closure, and so to the anchoring point on the bottom.

In the construction illustrated by Fig. 7, the existing single lift 21 of a water type holder with its base 22 is retained in the case where it is desired to provide a holder of greater capacity. The existing supports of the water type holder in which the "lift" or "lifts" were arranged to move vertically are removed and may be utilized in the construction of the stationary tank 11. A ring plate 4" of the proper outer diameter is attached to the crown of the lift 21, making with it a gas-tight joint. The cables 3" are fixed to the upper part of the tank and the foundation or base of the holder as shown and arranged to pass under and over the guide pulleys 5" and 6" respectively. Sealing means as described above are provided where the cables pass from the upper to the lower zone of the holder. The existing arrangements for introducing and exhausting gas from the holder are of the usual construction and are not shown as no departure from standard practice is made in this connection.

It will be apparent that the cables 3" may be arranged to pass from the top to the bottom centrally of the lift 21, as illustrated in Figs. 4, 5 and 6, and similar sealing arrangements provided.

More than one of the existing lifts of the old holder which were of the multiple lift type may, as will be apparent, be utilized.

I claim:

1. In a waterless gasholder of the piston-closure type comprising a tank and a piston closure for said tank, means for maintaining said piston closure in a normal horizontal plane, said means comprising at least three flexible cables each having its opposite ends connected respectively to the base and to the upper part of the tank at points substantially equidistantly spaced from the other cables on the upper part and the base respectively, and guide means carried by the piston closure at different points spaced transversely and circumferentially thereof through which the cables are movable, the intermediate part of each cable engaging said guide means and extending transversely of the piston closure and the other parts of each cable passing from the piston closure vertically to the top and bottom respectively of the tank.

2. In a waterless gasholder of the piston-closure type comprising a tank, a piston-closure for said tank, means comprising at least three

flexible cables for maintaining said piston closure in a normal horizontal plane, each of said cables having one of its ends extended upwardly from the piston closure and secured to the upper part of the tank and its other end extended downwardly from the piston closure and secured to the base at points substantially equidistant from the other cables, and guide means carried by the upper surface of the piston closure at different points on a diameter thereof and movably connecting the intermediate part of each cable to the piston closure at at least two points on a diameter of the latter.

3. A waterless gasholder as claimed in claim 2 wherein the guide means carried by the upper surface of the piston closure and movably connecting the intermediate part of each cable to the piston closure are located at diametrically opposed points on the periphery of the piston closure.

4. In a waterless gasholder of the piston-closure type comprising a tank, a piston closure for said tank, at least three flexible cables each fastened at one of its ends to the upper part of the tank and at its other end to the base of the holder at points spaced substantially equidistantly from the other cables with the intermediate portion of its length extending diametrically across the upper surface of the piston closure and through the same, means carried by the piston closure and located at different points on a diameter thereof for movably connecting the intermediate diametrically extending portion of each cable to the piston, and means forming a gas seal around each of said cables where it passes through the piston closure.

5. In a waterless gasholder of the piston-closure type comprising a tank, a piston closure for said tank, at least three flexible cables each fastened at one of its ends to the top of the holder and at its other end to the base of the holder at points substantially equidistant from the other cables and having its intermediate portion extending radially across the upper surface of the piston closure and through the same, guide means carried by the piston closure and located at different points spaced transversely thereof for movably connecting each cable to the piston closure, and means forming a gas seal around said cables where they pass through the piston closure.

6. In a waterless gasholder of the piston-closure type comprising a tank, a piston closure for said tank, said piston closure having a central opening, at least three flexible cables each having one of its ends fastened to the upper portion of said tank and its other end to the base of the holder at points substantially equidistant from the other cables and having its intermediate portion extending radially across the upper surface of the piston and through the central opening of the piston, means carried by the piston for movably connecting each cable to the piston, an open ended annular liquid-containing chamber fixed on the piston and surrounding said centrally disposed opening, a cylindrical member extending downwardly into said chamber concentrically therewith, and a plurality of guide pulleys, one for each of said cables, attached to the lower portion of said cylindrical member.

7. In a waterless gasholder having a shell and piston movable relative to one another, a plurality of pulleys mounted adjacent the periphery of the piston, and guide means comprising a plurality of flexible cables, each cable being secured at

its ends to the top and bottom respectively of the shell at points vertically aligned with the nearest pulley on the piston, and having its intermediate portion slidably connected to the piston at diametrically spaced points by the pulleys nearest to the ends of the cables.

8. In a waterless gasholder having a shell and piston movable relative to one another, a plurality of pulleys mounted adjacent the periphery 5 of the piston, and guide means comprising a

plurality of flexible cables, each cable being secured at its ends to the top and bottom respectively of the shell at points vertically aligned with the nearest pulley on the piston, and having its intermediate portion slidably connected to the piston at points spaced transversely and circumferentially thereof by the pulleys nearest to the ends of the cables. 5

EDWARD LLOYD PEASE. 10
